231,731

VEHICLE BODY

Paul H. Deesen, Rochester, Michael W. Lathers, Bloomfield Hills, Kent W. Madill, Oak Park, and Pierre Ollier, Bloomfield Hills, Mich., assignors to General Motors Corporation, Detroit, Mich.

Filed Nov. 20, 1972, Ser. No. 308,265

Term of patent 14 years

Int. Cl. D12—08
U.S. Cl. D12—100

Fig. 5

Fig. 4

FIG. 1 is a right side elevational view of a vehicle body showing our new design;

FIG. 2 is an enlarged front elevational view taken generally along the plane indicated by line 2—2 of FIG. 1;

FIG. 3 is a left side elevational view;

FIG. 4 is an enlarged rear elevational view taken generally along the plane indicated by line 4—4 of FIG. 1;

FIG. 5 is a top plan view taken generally along the plane indicated by line 5—5 of FIG. 1; and

FIG. 6 is a perspective view thereof.

The broken lines in the drawing are for illustrative purposes only.

We claim:

The ornamental design for a vehicle body, substantially as shown and described.
